COMBINED MILK CAN AND CLOSURE CAP THEREFOR

Ben J. Rosenthal, Fayetteville, Tenn.

Application July 6, 1955, Serial No. 36,836

Term of patent 3½ years

(Cl. D58—17)

FIG. 1.

FIG. 2.

Fig. 1 is a front elevational view of a combined milk can and closure cap therefor, showing my new design;

Fig. 2 is a vertical cross-sectional view thereof, a portion of the cap being shown broken away for purpose of illustration;

Fig. 3 is a top plan view thereof a portion of the cap being shown broken away for purpose of illustration;

Fig. 4 is a side elevational view thereof; and

Fig. 5 is a bottom plan view thereof.

The rear and side of the can not shown are the same as the front and side shown.

I claim:

The ornamental design for a combined milk can and closure cap therefor, substantially as shown and described.
